UNITED STATES PATENT OFFICE.

FRANK LOWRY, OF LOUDONVILLE, OHIO, ASSIGNOR TO THE OHIO GREASE COMPANY,
OF LOUDONVILLE, OHIO, A CORPORATION OF OHIO.

DROP-FEED LUBRICATOR.

1,156,488.

Specification of Letters Patent.

Patented Oct. 12, 1915.

Application filed June 22, 1914. Serial No. 846,459.

To all whom it may concern:

Be it known that I, FRANK LOWRY, a citizen of the United States, residing at Loudonville, in the county of Ashland and State 5 of Ohio, have invented certain new and useful Improvements in Drop-Feed Lubricators, of which the following is a specification.

The invention relates to lubricators for 10 feeding grease, oil or other similar lubricants into the steam line or steam chest of an engine; and the object of the present invention is to provide a lubricator which will not only completely heat and liquefy the lubricant for feeding in small sized drops, but to further heat and to more completely vaporize or atomize the same than has heretofore been done by previous devices of this character.

20 The object of the improvement is attained by locating the feed chamber within the grease chamber, with a vertical straightway feed port in the upper end of the feed chamber, and a lateral discharge tube leading 65 from the lower end of the feed chamber to the steam line; by inclining the bottom of the feed chamber upward from the discharge pipe, directly underneath the feed port, for receiving the lubricant dropping 70 therefrom; and by carrying a steam heating pipe transversely through the upper end of the grease chamber, into the upper end of the feed chamber, and providing a pendent baffle plate in the upper end of the feed 75

30 near the end of the steam pipe for shielding the feed port and directing the steam downward along and across the inclined bottom of the chamber where the lubricant drops thereon, for atomizing and vaporizing the 80 same, and carrying the vapor lubricant through the discharge pipe into the steam line.

35 A preferred embodiment of the invention is illustrated in the accompanying drawing, 85 forming part hereof, in which

Figure 1 is a vertical section of the improved lubricator; and Fig. 2, a transverse section of the same on line 2-2, Fig. 1.

Similar numerals refer to similar parts 90 throughout the drawing.

The grease reservoir or chamber 1 is formed by the case 2 of the lubricator, and the feed chamber 3 is formed by the wall 4 within the grease chamber; which wall 45 of the feed chamber may be located wholly

within the case of the grease chamber, but may have one side thereof formed integral with the case thereof, as shown in the drawing.

The upper end 5 of the feed chamber is 60 preferably located at a substantial interval below the upper end 6 of the grease chamber, so that the vertical straightway port 7 may be provided in the upper end of the feed chamber leading directly downward 65 from the upper end of the grease chamber above the feed chamber, which port is preferably opened and closed by means of the feed valve 8; and the pendent nipple 9 is preferably provided in the lower end of the feed port, for more definitely forming a small drop of lubricant as the same passes through the port, sight glasses 9^a preferably being provided in each side of the feed chamber through which the lubricant dropping 70 from the nipple may be seen.

75 The discharge tube 10, extends from the lower end of the feed chamber to the steam supply pipe 11, and is preferably provided with the stop valve 12, as shown in the drawing. The inclined surface 13 is provided in the feed chamber directly below the nipple in the lower end of the feed port, so that drops of lubricant will fall and spread upon the surface before passing downward into 80 the discharge tube. This surface may be formed as part of the bottom of the feed chamber, as shown, but this particular construction is not essential.

85 The transverse steam heating pipe 14 is located in the upper end of the grease chamber, with its inner end leading into one side of the upper end of the feed chamber and its outer end communicating with the steam supply line 11 at a point above the entrance 90 of the discharge tube therein, as by means of the steam pipes 14^a and 14^b; the former of which pipes may be controlled by the valve 15, and the latter one by the valve 16. The steam pipe 14^b is also in communication 95 with the condensing pipe 17, which may be provided with the condensing chamber 18 and leads to the condensing tube 19, opening into the lower end of the grease chamber, in a manner well known in this art.

100 The transverse baffle plate 20 depends from the upper end of the feed chamber, in front of and across the entrance of the steam heating pipe therein; which plate serves to 105 protect the end of the nipple from the in-

coming flow of steam, and permit the formation of drops of lubricant thereon, and to prevent the steam from wearing away the surfaces of the sight glasses 9^a, and also 5 to direct the flow of steam downward along and across the inclined surface in the feed chamber below the feed nipple, for the purpose of constantly heating the same, and also to impinge the drops of grease as the same 10 spread out upon the inclined surface, for superheating, atomizing and vaporizing the same, and carrying the resulting vapor lubricant through the discharge tube into the steam supply line.

15 It is evident that the presence of the transverse heating tube in the upper end of the grease chamber serves to completely liquefy the grease therein, at a point where it may flow directly downward through the feed 20 port 5 to form a drop on the end of the nipple in the feed chamber; and that the highly heated condition of the lubricant in the upper end of the grease chamber, and the avoidance of any chilling thereof, in 25 passing through the feed port, permit the drops to form while the lubricant is in a very thin or watery condition, so that drops of a minimum size will be formed, and a more refined regulation of the feed can be 30 attained. And it is evident, that when the small drops of lubricant fall upon the highly heated inclined surface, they will not only spread upon and be instantly superheated by the same, but will be impinged by the down- 35 wardly deflected flow of steam from the heating pipe, with the result that the thin film of liquid lubricant upon the plate will be completely atomized and vaporized by the steam, and carried therewith in the form 40 of a vapor lubricant through the discharge tube into the steam supply line.

I claim:

1. A lubricator including an outer case forming a grease chamber, a wall forming a 45 feed chamber within the grease chamber, a feed port leading directly downward from the grease chamber into the upper end of the feed chamber, a discharge tube leading from the lower end of the feed chamber, and a 50 steam tube leading through the upper end of the grease chamber into the upper end of the feed chamber.

2. A lubricator including a feed chamber having a pendent nipple in its upper end, a 55 discharge tube leading from its lower end

and a steam tube leading into its upper end, the bottom of the feed chamber being inclined in the path of drops falling from the nipple, and a baffle plate shielding the nipple and directing the steam along and across the 60 inclined bottom.

3. A lubricator including a feed chamber having a pendent nipple in its upper end, a discharge tube leading from its lower end and a steam tube leading into its upper end, 65 the bottom of the feed chamber being inclined in the path of drops falling from the nipple, and a baffle plate directing the steam along and across the inclined bottom.

4. A lubricator including a feed chamber 70 having a pendent nipple in its upper end, a discharge tube leading from its lower end, an inclined surface in the feed chamber in the path of drops falling from the nipple, and a baffle plate shielding the nipple and directing the steam along and across the inclined surface.

5. A lubricator including a feed chamber having a pendent nipple in its upper end, a 80 discharge tube leading from its lower end and a steam pipe leading into its upper end, an inclined surface in the feed chamber in the path of drops falling from the nipple, and a baffle plate directing the steam along 85 and across the inclined surface.

6. A lubricator including an outer case forming a grease chamber, an inner wall forming a feed chamber, a feed port leading from the grease chamber into the upper end 90 of the feed chamber, a discharge tube leading from the lower end of the feed chamber, a steam pipe leading into the upper end of the feed chamber, and a baffle plate diverting the flow of steam from the feed port and 95 directing it toward the discharge tube.

7. A lubricator including an outer case forming a grease chamber, an inner wall forming a feed chamber, a feed port leading from the grease chamber into the upper 100 end of the feed chamber, a discharge tube leading from the lower end of the feed chamber, a steam pipe leading into the upper end of the feed chamber, and a baffle plate diverting the flow of steam from the feed port. 105

FRANK LOWRY.
